DESIGN FOR A GAME BOARD

James Glenn Rolley, New York, N. Y.

Application October 28, 1944, Serial No. 116,017

Term of patent 14 years

(Cl. D34—5)

To all whom it may concern:

Be it known that I, James G. Rolley, a citizen of the United States of America, residing at New York city, county of New York and State of New York, have invented a new, original, and ornamental Design for Game Boards, of which the following is a specification, reference being had to the accompanying drawing, forming part thereof.

Figure 1 is a top plan view of the game board showing my new design.

Figure 2 is a side elevation thereof.

Figure 3 is a longitudinal section on the line A—A of Figure 1.

Figure 4 is a cross section on the line B—B of Figure 1.

I claim:

The ornamental design for a game board, as shown.

JAMES GLENN ROLLEY.
